UNITED STATES PATENT OFFICE.

HARRY J. BUTLER, OF SAN JOSE, CALIFORNIA.

LADDER-TRUCK.

1,113,100.

Specification of Letters Patent.

Patented Oct. 6, 1914.

Application filed January 30, 1914. Serial No. 815,472.

To all whom it may concern:

Be it known that I, HARRY J. BUTLER, a citizen of the United States, residing at San Jose, in the county of Santa Clara and State of California, have invented certain new and useful Improvements in Ladder-Trucks, of which the following is a specification.

This invention relates to ladder trucks, and its object is to produce by means of ladders having special construction and arrangement a structure capable of being elevated and lowered and provided with a platform at the top when the ladders are raised.

It is also an object of this invention to provide a third or additional ladder arranged to extend laterally, and to be raised or lowered with the other parts, in order that the truck equipped with this invention may be run up to a burning building, and the additional or third ladder extended, not only to those windows upon a level with it, but to the windows above or below it, for the passage of the firemen or the escape of persons endangered by the fire.

Throughout the following description and in respect of this invention, it will be understood that the word "ladder" is intended to mean a ladder of any known construction that may be employed, whether or not it is an extension ladder comprising a number of sections, or a single continuous ladder of common form.

The construction and arrangement of parts comprising this invention is set forth in the accompanying drawings, whereof—

Figure 1 represents a side view of the rear portion of a truck having this invention applied thereto. All parts appear assembled and the ladders are in their lowered positions. Fig. 2 is a cross-section on the line $x-x$ of Fig. 1 to show the movable connection of the foot of the second ladder with the supporting rails on the turntable. The connection of the operating cable with the second ladder is also shown in Fig. 2. Fig. 3 is a side view of the rear portion of a truck having this invention applied thereto. All parts are assembled, and the ladders are shown raised and extended.

Throughout the description and drawings, the same letter is employed to refer to the same part.

Considering the drawings, a truck A has a turntable a , and upon the turntable are the supporting rails B and b , each provided

with a horizontal series of holes such as the holes C in rail B in Fig. 1.

A platform D has pivotally connected with a ladder d . The foot of the ladder d is pivotally connected with ladder-raising mechanism E , including a swinging arm e . The mechanism E comprises also a pinion F on the same transverse shaft f with a sprocket wheel G . A chain g connects the sprocket wheel G with a like wheel H on the lower transverse shaft h . The shaft h also has a pulley J upon it, and about the pulley extends the endless operating cable j , that passes around the pulley K at the other ends of the rails B and b . The cable j has a connection k with the transverse shaft L , as best shown in Fig. 2, which takes the place of the lowest rung of the ladder M , and upon which that ladder may be swung up and down. The ladder M is the second ladder mentioned in this description. At the ends of the shaft L are rollers m that run upon the lower inside flanges of the rails B and b , as the ladder M is raised and lowered.

A third ladder N is pivotally joined to the platform D as shown, and is provided with side braces n , having bolts O for the purpose of securing the braces n in different positions. That is accomplished by passing the bolt O through the brace and through the holes C in the rail B . The other brace, not shown is similarly provided with a bolt and for the same purpose. The third ladder N is provided with light but very strong hinged leaves, such as the leaf P shown in Fig. 1. These leaves are turned inwardly when the third ladder N is extended, and constitute a floor over which a person may walk safely to the platform D , even though the ladder may have some inclination up or down with respect to the platform. In practice it is usual to provide the third ladder N with a hand rail as illustrated. It is often desirable to raise and lower the third ladder N from the platform, and for that purpose there is provided on the platform the windlass Q , to take up and pay out the cable R that has its outer end attached to one of the rounds of the ladder N near the outer end of the ladder.

The remaining parts of this invention are best described in connection with the explanation of the mode of operation. Let it be supposed that the bolts O have been removed, the truck being in the position de-

sired, which will free the lower ends of the braces. This may be quickly done. It will be noted in Fig. 1 that the ladders *d* and *M* in their closed positions are held separated 5 near the platform by means of the spacing and supporting frame *S* attached to the ladder *d*. This arrangement is made to permit the substantially horizontal disposition of the ladders in their closed positions, thus 10 presenting a more attractive and regular appearance, and, further, it is found in practice relatively easier to start the raising movement of the ladders from such position. In Fig. 1 is also illustrated the extension *T* 15 of the foot of the ladder *d*, and the balance weight *t* advantageously employed to aid the raising movement. By means of the crank *U* the shaft *f* is revolved, and the pinion *F* works its way to the right in mesh with the 20 curved rack *u* of the ladder-raising mechanism *E*, drawing with it the foot of the ladder *d*, and raising the two ladders *d* and *M* into the positions indicated by the broken lines 1, 2 and 3 in Fig. 3. In Fig. 1 it will 25 be seen that the transverse shaft *f* is in a higher position than the pivotal junction of the platform *D*, and, therefore, the drawing of the ladder *d* to the right, by means of the crank *U*, the shaft *f*, and the pinion *F* 30 in the rack *u*, pulls upwardly upon the left-hand end or top of the ladder *M*, which, as shown in Fig. 1, rests at a higher point than its right-hand end or foot. The ladder *M* cannot slip toward the right, being held 35 by the transverse stop-bar *y* shown upon the lower edge of the rail *B* against the connection *k*. The weight *t* materially assists the raising operation, and, when special haste is called for, the raising and adjusting may 40 be expedited by the hands of the firemen. Now, the pinion *F* runs off the rack *u* and against the stop *r*, and, upon continuing to turn the crank *U*, the sprocket wheels *G* and *H* connected by the chain *g*, and operating 45 the cable *j*, all of which have been moving during the operation just explained, bring the stop *V* on the cable *j*, in contact with the connection *k* at the foot of the ladder *M*, and the foot of the ladder is moved into the 50 position illustrated in Fig. 3. During the operations of raising and lowering the ladders *d* and *M*, the movements of the feet of those ladders are in opposite directions. It is believed to be discernible from the foregoing and the drawings that on reversal of 55 the movement of the crank *U*, the stop *W* is brought against the connection *k* from the other side, and the foot of the ladder *M* is moved again into the position shown in Fig. 60 1. The natural fall of the ladders *d* and *M* reengages the pinion *F* and the rack *u*, and the ladders may be lowered rapidly or more slowly as desired.

When the ladders *d* and *M* are positioned 65 as set out in Fig. 3, weight upon the plat-

form *D* tends to spread the ladders farther apart at their feet. Such spreading is resisted, for the ladder *d*, by the contact of the swinging arm *e* and the endpiece *w* of the rails *B* and *b*. For the ladder *M*, the spreading stated is opposed by the coupling of the ladder *M* and the crossbar *Y* connecting the rail *B* by bolt *O*, best shown in Fig. 3.

The third ladder *N*, it will be readily understood from the drawings, may be raised or lowered by the windlass *Q*, and, in practice the outer end of the third ladder is occasionally provided with a canvas chute fire escape *Z*, of ordinary construction and operation.

Having now described this invention, and explained the mode of its operation, I claim:

1. In a ladder truck, the combination with a turntable, of supporting rails carried by the turntable, a movable platform, a ladder pivotally connected with one side of the said platform, a second ladder pivotally connected with the other side of the said platform, ladder-operating mechanism constructed to move the foot of the first-mentioned ladder, the said mechanism having a portion located when the said ladders have been lowered at a higher point than the junction of the second ladder and the said platform whereby a pull is applied to the said second ladder and platform to raise them, the foot of the said second ladder having a movable connection with the said supporting rails, and means for moving the foot of the second ladder in the opposite direction to the movement of the foot of the first-mentioned ladder.

2. In a ladder truck, the combination with a turntable, of supporting rails carried by the turntable, a movable platform, a ladder pivotally connected with one side of the said platform, a second ladder pivotally connected with the other side of the said platform, ladder-operating mechanism constructed to move the foot of the first-mentioned ladder, the said mechanism having a portion located when the said ladders have been lowered at a higher point than the junction of the second ladder and the said platform whereby a pull is applied to the said second ladder and platform to raise them, the foot of the said second ladder having a movable connection with the said supporting rails, and means for moving the foot of the second ladder in the opposite direction to the movement of the foot of the first-mentioned ladder.

3. In a ladder truck, the combination with a turntable, of supporting rails carried by the turntable, a movable platform, a ladder pivotally connected with one side of the said platform, a second ladder pivotally connected with the other side of the said platform, ladder-operating mechanism constructed to move the foot of the first-mentioned ladder, the said mechanism including a vertically-swinging arm connected pivotally at one end to the foot of the said first-mentioned ladder and at the other end with the said rails, the said mechanism having a portion located when the said ladders have been lowered higher than the junction of the second ladder and platform whereby a pull is applied to the second ladder and platform to raise them, the foot of the said second ladder having a movable connection with the said supporting rails, and means for moving the foot of the said second ladder in the opposite direction to the movement of the foot of the first-mentioned ladder.

3. In a ladder truck, the combination with a turntable, of supporting rails carried by the turntable, a movable platform, a ladder pivotally connected with one side of the

said platform, a second ladder pivotally connected with the other side of the said platform, a third ladder pivotally connected with the said platform on the same side 5 with the said first-mentioned ladder, ladder-operating mechanism constructed to move the foot of the first-mentioned ladder, the said mechanism having a portion located when the said ladders have been lowered at a point higher than the junction 10 of the said second ladder and the said platform whereby a pull is applied to the said second ladder and platform to raise them, the foot of the said second ladder having a 15 movable connection with the said rails, means for moving the foot of the said second ladder, side braces pivotally connected at one end with the said third-mentioned ladder, and means for connecting the said 20 braces and rails at different points.

4. In a ladder truck, the combination with a turntable, of supporting rails carried by the said turntable, a movable platform, a ladder pivotally connected with one side

of the said platform, a second ladder pivotally connected with the other side of the said platform, ladder-operating mechanism constructed to move the foot of the first-mentioned ladder, the said mechanism having a portion located when the said ladders 25 have been lowered at a point higher than the junction of the said second ladder and the said platform whereby a pull is applied to the said second ladder and platform to raise them, the foot of the said second ladder having a 30 movable connection with the said rails, and means actuated by the said ladder-operating mechanism for moving the foot of the said second ladder after the movement of the foot of the said 35 first-mentioned ladder has been completed.

In testimony whereof I affix my signature in presence of two witnesses.

HARRY J. BUTLER.
